(57) **CLAIM**

The ornamental design of a phacoemulsification handpiece as shown and described.

DESCRIPTION

FIG. 1 is an isometric view of the phacoemulsification handpiece of the present invention.

FIG. 2 is a first side view of the phacoemulsification handpiece of the present invention.

FIG. 3 is a front view of the phacoemulsification handpiece of the present invention.

FIG. 4 is a rear view of the phacoemulsification handpiece of the present invention.

FIG. 5 is a top view of the phacoemulsification handpiece of the present invention.

FIG. 6 is a bottom view of the phacoemulsification handpiece of the present invention; and,

FIG. 7 is a second side view (opposite side as FIG. 2) of the phacoemulsification handpiece of the present invention.

The broken lines in the drawings indicate portions of the phacoemulsification handpiece that form no part of the claimed design.

1 Claim, 4 Drawing Sheets
